DISH-WASHING MACHINE

Myron C. Rogers, Morrison, Ill.

Original application August 25, 1931, Serial No. 559,285. Divided and this application January 8, 1934, Serial No. 705,803

2 Claims. (Cl. 299—63)

This application is a division of an application filed by me August 25, 1931, Serial No. 559,285, and which eventuated January 9, 1934 in Letters Patent No. 1,942,452.

5 This invention relates to dish washing machines and has for an object to provide a machine of this type which will be devoid of screens or other filters that might clog up, will be devoid of exposed rotating worms, and will be of such accessible construction as to be cleansed and kept in a 10 sanitary condition with minimum effort.

15 A further object is to provide a distributor cap which forms a closure for the top of the pump housing and which is attached to the pump and is positively rotated by the pump, the cap being adapted to throw a large volume of water over the dishes so that the dishes are quickly and effectively washed.

20 With the above and other objects in view the invention consists in certain novel details of construction and combinations of parts hereinafter fully described and claimed.

25 In the accompanying drawings forming part of this specification,

25 Figure 1 is a sectional view through a dish washing machine constructed in accordance with my invention.

Fig. 2 is a side elevation of the rotary distributor cap.

30 Fig. 3 is a cross sectional view on the line 3—3 of Fig. 2.

Fig. 4 is a fragmentary perspective view showing the bearing of the distributor cap.

35 Fig. 5 is an enlarged sectional view of the cap taken on the line 5—5 of Fig. 1.

Fig. 6 is an enlarged cross sectional view taken on the line 6—6 of Fig. 1, showing the leading edges of the openings in the pump housing sharpened.

40 Referring now to the drawings in which like characters of reference designate similar parts in the various views, the washing machine is shown to comprise a frame including an angle iron ring 18 to which are preferably riveted four castered legs 11. The flange of the angle iron ring forms a supporting ledge for a container 12 which preferably is formed of metal and is closed by a cover 13. The bottom 14 of the container is depressed from the outer edge toward the center and, at the center, is further depressed to receive a rubber packing washer 15, and at the center is provided with an opening 16.

45 The pump housing 17 is preferably formed of a cylinder of uniform diameter, the cylinder being open at the top and being closed at the bot-

tom by a flat disk 18 which bears upon the rubber washer 15. Above the bottom disk there are formed a plurality of elongated circumferential openings 19 in the wall of the housing, preferably three of such openings being provided, as best shown in Fig. 6. The webs 20 of the housing between the openings preferably are sharpened, as shown at 21, on the leading edges to promote easy access of the water into the pump housing in a counter-clockwise direction to correspond to the direction of rotation of the hereinafter described spiral pump 22.

5 The webs 20 of the housing there is a nipple 23 which is threaded exteriorly and is of sufficient size to loosely fit in the opening 16 in the bottom of the container. A packing nut 24 closes the lower end of the nipple. The bottom disk 18 is also provided on its top surface with an upstanding boss which extends in prolongation of the nipple 23. A nut 26 is threaded onto the nipple 23 and forms means for securing the pump housing to the bottom of the container. Obviously, by simply backing off the nut 26 the pump housing may be removed bodily from the container for cleansing when necessary.

20 The above-mentioned spiral pump 22 is vertically disposed in the pump housing to rotate in a counter-clockwise direction, the axial shaft 27 of the pump projecting at the upper end beyond 30 the spiral worm of the pump, as shown at 28, and also projecting below the lower end of the spiral worm, as shown at 29. The bottom extension 29 of the pump shaft is journaled for rotation in the above described boss and nipple 23 35 of the pump housing.

25 A shoulder 30 is formed on the pump shaft to seat on the top edge of the boss, as best shown in Fig. 1, and thereby limit insertion of the pump in the housing. It will thus be observed that the 40 spiral worm of the pump terminates at the upper end flush with the top of the housing and terminates at the lower end flush with the top of the boss which, as will be observed, extends above the tops of the lateral openings 19 in the housing. 45

Thus, the spiral worm is elevated above the intake openings 19 so that whatever sediment may accumulate in the bottom of the container will not be touched by the worm and carried up in the housing as would be the case were the worm 50 extended to the bottom wall of the housing to cut into the accumulated sediment. Furthermore, by the spiral worm being elevated above the intake openings 19, should the fingers of the operator or children be inserted in the openings, 55

they will not encounter the worm as the worm is completely housed by the housing and is not exposed through the openings, so that no injury will result.

5 In further carrying out the invention, I provide a distributor cap 31, best shown in Figs. 1, 2 and 5, which forms a closure for the top of the housing 17, and is provided with a cylindrical side wall 32 which fits loosely down over the 10 outer face of the top of the housing so that the cap may rotate freely thereon. The wall is thickened at the bottom to provide an annular bearing 33, as shown in Fig. 4. The bearing engages the housing 17 and is lubricated by water 15 passing downward through grooves 36 in the bearing so that oiling of the bearing is unnecessary.

The wall of the distributor cap is preferably provided with a pair of opposite elongated openings 34 which extend longitudinally of the wall. 20 It is also preferably provided with a pair of opposite openings 35 of less length than the openings 34, as best shown in Fig. 2. It will be observed that both pairs of openings extend vertically and provide slits through which the water will discharge with great force. To permit streams of water being thrown downwardly, the vertical grooves 36 are formed in the bearing 33, as best shown in Fig. 3. Also, it will be observed 25 that the top of the cap is substantially dome-shaped and is constructed at about a medial point to provide an external annular V-shaped groove 37, the bottom of which is perforated, as shown at 38, to provide jet openings through which the 30 water may escape horizontally.

The distributor cap is positively rotated by the pump, so that all the streams of water will be revolved while being simultaneously ejected in large volume and with great force.

40 For rotating the cap, the upper end of the extension 28 of the spiral pump shaft 27 is reduced and squared, as shown at 39 in Fig. 1. A square opening 40 formed at the center of the cap receives said squared end of the shaft. A nut 41 is threaded onto the end of the shaft and secures the cap firmly on the shaft. The cap thus rotates as a unit with the worm pump in a counter-clockwise direction. By simply removing the nut 41, the cap may be quickly removed for cleansing 45 when desired.

By referring now more particularly to Fig. 1 it will be seen that a motor 42 is mounted on the frame of the washing machine below the container and between the legs thereof. A spider, 50 preferably having four arms 43 connected at the inner ends by a split clamp ring 44, is employed to secure the motor to the legs 11. Angle iron brackets 45 are preferably riveted to the legs and bolted to the outer ends of the spider arms. The 55 clamp ring 44 surrounds the motor casing and is tightly secured thereto by means of a bolt which connects the terminals of the ring. Inclined braces 46 are terminally connected to the legs 11 of the washing machine and to the arms 43 of the spider. The spider serves to removably support the motor as well as reinforce the motor 60 against horizontal vibration.

To secure the motor against vertical vibration, a spider is employed, having a central disk 47 which is perforated at the center to receive the nipple 23. The spider is provided with preferably four arms 48, which extend downwardly at the ends, and are terminally secured by screws, or otherwise, to the motor casing. A rubber washer 75 49 is inserted on the nipple 23 between the disk

47 and bottom of the container 12. It will be observed that the nut 26 may be backed off from the nipple to permit removal of the pump, housing and distributor cap as a unit from the container 12 without disturbing the position of the spider 47.

To connect the motor shaft 50 with the bottom extension 29 of the spiral pump, I employ a tubular sleeve which is secured to the motor shaft by means of a set screw 52 and which projects up into the nipple 23 through the stuffing box 24. The sleeve is coupled to the shaft of the spiral pump by means of a tongue and groove connection between these parts, designated in general by the numeral 53.

10 It will be observed that this tongue and groove connection 53 permits removal of the spiral pump 22 from the housing 17 by simply lifting the cap 31 and spiral pump vertically as a unit from the housing, and that to accomplish this result it is 15 not necessary to remove any screws, nuts or similar connectors.

20 Within the container 12 there is disposed a basket preferably formed of wire mesh and comprising a wire frame including a plurality of stiff vertical wires 54 connected at the top and bottom by wire rings 55. Wire mesh 56 of suitable stiffness may be securely attached to the frame in any preferred manner, such as by spot-welding or otherwise, to form the wall and bottom of the 25 basket. To facilitate centering the basket in the container, a skeleton frame is mounted centrally in the basket and comprises a plurality of vertical wires 57 which are connected at the top and at the bottom by wire rings 58 of greater diameter than the outer diameter of the pump housing 17, 30 as best shown in Fig. 1.

35 Disposed on the bottom of the basket there are a plurality of stiff wire frames 59 of the general shape shown in Fig. 1. The inner legs of the frames are connected together by a wire ring 60, while the outer legs of the frames are connected to the outer bottom wire ring 55 of the basket. The frames constitute racks between which the dishes may be placed.

40 A plurality of plates 61 are disposed on the bottom of the basket and may be rigidly connected thereto in any preferred manner. These plates gradually increase in depth from the outer to the inner ends, so as to support the bottom of the 45 basket level on the sloping bottom 14 of the container. The plates thus form supports for the basket, and it will be observed that the plates extend from the wall of the container 12 to the pump housing 17 and thus also perform the function of baffles which positively prevent any swirling of the water being sucked into the housing by rotation of the pump.

50 The container 12 is properly centered and supported on the angle iron ring 18 by means of a 55 resilient flange 62 which is faced on the inner side with a rubber ring 63 adapted to bear against the wall of the container. The flange 62 may be riveted, as shown at 64, or otherwise rigidly secured to the angle iron ring 18.

55 A drain pipe 65 enters the bottom of the container and is controlled by a valve 66.

60 In operation, the container is partially filled with hot water containing soap powder or other desired cleansing agent. The dishes are then 65 placed in position in the basket, or this may be done before the water is supplied, if desired, and then the cover 13 is placed on the container. The motor is then started, rotating the spiral pump 70 75 75, and causing a continuous and forceful ejec-

tion of the water upward in the housing 17 against the cap 31 and out through the openings thereof.

The streams ejected from the openings have 5 a whirling motion due to the positive rotation of the cap by the spiral pump, and these streams pass outwardly and downwardly to all parts of the container, finding their way to all parts of the dishes in the basket, even to the insides of 10 cups and similar dishes, and thoroughly cleansing the same.

Since the baffles 61 prevent swirling of water in the bottom of the container, any sediment will not be stirred up but will be deposited on the 15 bottom of the container.

It is thought that from the above description the construction and operation of my invention will be thoroughly understood without further explanation.

20 Having thus described the invention, I claim:
1. In a dish washing machine, a cylindrical pump housing, a spiral pump in the housing, a distributor cap rotatably mounted on the top of the housing and operatively connected to the 25 pump for rotation therewith as a unit, said cap having a wall provided with discharge openings,

and an internal annular bearing flange on the cap below the openings in its wall rotatably engaging the housing, said flange having vertical grooves extending from its top edge to its bottom edge and in communication with the interior of the cap to permit the downward flow of water from the cap to lubricate the bearing.

2. In a dish washing machine, an upright pump housing open at the top, a spiral pump in the housing, a distributor cap having a dome-shaped cap extending over the open top of the housing and provided externally with a V-shaped annular groove and jet openings in the bottom of the groove, said cap having a cylindrical skirt wall surrounding the housing, said wall being 15 thickened at the bottom and constituting a bearing which rotatably engages the housing, there being vertically extended elongated discharge openings in said wall to discharge water laterally, and there being vertical discharge grooves formed 20 in said bearing constructed and arranged to cause water to flow downwardly and lubricate the bearing.

MYRON C. ROGERS. [L. S.]
